UNITED STATES PATENT OFFICE.

PARVIN WRIGHT, OF DENVER, COLORADO, ASSIGNOR OF SEVENTY ONE-HUNDREDTHS TO PETER C. HORN AND CECELIA R. NORTHROP, BOTH OF SAME PLACE.

TELEPHONE.

SPECIFICATION forming part of Letters Patent No. 390,428, dated October 2, 1888.

Application filed March 6, 1888. Serial No. 266,347. (No model.)

To all whom it may concern:

Be it known that I, PARVIN WRIGHT, a citizen of the United States, residing at Denver, county of Arapahoe, State of Colorado, have 5 invented certain new and useful Improvements in Telephones, of which the following is a specification.

The object of my invention is to provide an 10 improved telephone capable of transmitting speech with large volume, great distinctness, and sufficient energy to work on long lines.

Briefly stated, my invention consists in providing a telephone with an electro-magnet the coils of which are included in an electric 15 circuit, and providing resistance devices in an independent circuit operated upon in an improved way by the electro-magnet to vary their conductivity. This organization of apparatus may be employed in connection with 20 a telephone-transmitter by including in the ordinary local circuit of the transmitter an electro-magnet adapted to act upon the resistance devices in an independent circuit, which may constitute the main line, or which may include the primary of an induction-coil.

A telephone-receiver may embody my invention by having an electro-magnet adapted to act upon resistance devices arranged in an independent circuit which includes a local 30 battery and the electro-magnet for vibrating the diaphragm.

My invention may also be used in a telephone-relay by connecting the coils of an electro-magnet to the main line, providing resistance devices acted upon by the electro-magnet, and including the resistance devices 35 in an independent circuit.

In the accompanying drawings, illustrating my invention, Figure 1 is a view, partly in 40 section, of a telephone-transmitter embodying my invention, showing also an induction-coil and the electric-circuit connection. Fig. 2 is a section of a telephone-receiver with my improvements applied, showing also the circuit-connections. Fig. 3 shows in section a telephone-relay embodying my improvements, and also the electric-circuit connections with the main line and a telephone-receiver. Fig. 4 is an end view of a transmitting-telephone, 45 showing a number of mouth-pieces.

Referring first to Fig. 1 of the drawings, which illustrates a telephone-transmitter embodying my invention, A indicates the mouth-piece of the telephone, B the diaphragm, and C the frame or casing, all of which may be of 55 any desired construction. D indicates a spring carrying an electrode, d, in contact with the diaphragm, and with an electrode or button, E, of some substance capable of variable electrical resistance—carbon, for instance. The local 60 circuit F, having a battery, G, includes the electrodes E d. The local circuit F also includes the coils of an electro-magnet, H, mounted in suitable supports in the frame C; or it may be located at a distance, if desired, and operatively 65 connected with the transmitting-diaphragm by the circuit F. The magnet is preferably provided with a hollow core, I, through which extends a rod, J, secured at one end to the armature K and at the other end to a metallic 70 plate, L. The core of the magnet projects from the coil and bears upon the plate L. N and O indicate resistance-blocks, preferably carbon, with a layer between them of powdered carbon and caoutchouc or other semi-conducting material, o, capable of variable 75 electrical resistance. The block O rests on a metallic plate, P, and against this block bears a set-screw, Q, mounted in the frame, and which may be used to adjust the blocks relatively to the armature K, and also vary the pressure between the blocks upon the powdered material, o. U indicates a rubber band stretched around the plates and blocks, serving to hold them in position, and also to retain 80 the powdered material, o. Those parts of the frame C which support electrical conductors included in the electric circuits are preferably 85 made of non-conducting material.

The terminals of a battery-circuit, R, are 90 electrically connected with the plates L and P, as shown, and thus include the resistance-blocks N and O and the powdered material, o, in the circuit. The circuit R may be used as the main-line circuit, or it may include the 95 primary of an induction-coil, S, the secondary of which includes the main line, as shown in the drawings.

It will be seen that the resistance device operated upon by the magnet H is separate 100

and distinct from the usual resistance or electrode devices of the transmitter-diaphragm.

When the diaphragm B is vibrated by air-waves, the current in the local circuit F will be varied and will produce corresponding variations in the electro-magnet H, thereby causing the core I to correspondingly expand and contract or lengthen and shorten, and also causing the armature K to vibrate coincidently with the transmitting-diaphragm. The expansion and contraction of the core and the vibrations of the armature cause corresponding variations in the pressure between the resistance-blocks N and O and the interposed semi-conducting material, o; but the effect is multiplied, as the contact-surface of the blocks is much larger than the contact-surface in the local transmitting-circuit F, and the mechanical force used to vary the pressure between the resistance-blocks in the second circuit, R, is enabled to control a much stronger battery in this circuit R, so that a large volume of sound is transmitted, and it is made clear and distinct at the receiving end of the line.

As above remarked, the electro-magnet, its armature, and the resistance-blocks need not be located in the frame C. As is indicated, by breaking away the frame C at e, Fig. 1, it may be made in two portions or separate structures, which may be located at any desired distance apart preferred and operatively connected with the transmitting-diaphragm by the circuit F. By multiplying the apparatus, as shown in Fig. 4, an increased effect is produced. Sounds taken up by the transmitter may be carried to different places over different lines; or the apparatus may be so arranged that the different transmitters may connect with the same main line.

Obviously other modifications may be made in the apparatus. The number of diaphragms, electro-magnets, and resistance devices may be increased, diminished, or varied at pleasure.

In connection with my improved transmitting apparatus I may employ a receiving-telephone so constructed as not to be affected by induced currents or statical electricity. This I accomplish by removing the diaphragm a suitable distance from the core of the magnet, so that it will be less sensitive and out of the reach of external influences, and still be within the strong magnetic field derived from my improved transmitter.

Referring now to Fig. 2 of the drawings, which illustrates my invention embodied in a telephone-receiver, A' indicates the casing; B', the ordinary diaphragm; C', the electro-magnet for vibrating the diaphragm. D' indicates a supplemental electro-magnet contained within the casing A', and having a core, E', rigidly secured at its inner end to the casing by means of set-screw F'. It may also be secured to the core G' of the electro-magnet C' by a set-screw, H'. a' b' indicate carbon blocks; c', powdered carbon and caoutchouc or similar semi-conducting material between the carbon blocks; d', a metallic plate, against which bears the core E'

of the magnet D'; e', a metallic plate which rests against the outer face of the carbon block b'. H' indicates a set-screw, which bears against the lower plate, e', and serves to adjust the blocks relatively to each other and to compress the powdered material between the blocks. x indicates the main line, which includes the electro-magnet D', as indicated. y indicates a local circuit, including a battery, Y, and the resistance devices, as indicated. As will be seen, the circuit y is electrically connected with electro-magnet G' and includes it in the circuit.

The operation of the receiver is similar to the operation of the transmitter—that is, the main-line current energizes the electro-magnet D'. This causes the core E to expand and contract, or lengthen and shorten, and thereby vary its pressure on the plate d', and consequently the pressure on the carbon blocks and the interposed powdered material. This variation in pressure varies the local circuit correspondingly to the variations in the main-line circuit, and consequently produces a corresponding variation in the electro-magnet C', causing it to vibrate the diaphragm B', to produce sound-waves similar to those produced at the transmitting end of the line.

Fig. 3 illustrates my improved telephone-relay. I' indicates the rigid frame or casing; K', an electro-magnet securely fastened at L' to the casing. M' indicates the core of the magnet, also rigidly secured to the casing at L', as shown. f' and g' indicate carbon blocks, between which may be arranged powdered carbon or similar material. h' and i' indicate metallic plates on the outer faces of the carbon blocks. The screw N' may be arranged to bear against the plate i' to regulate the pressure between the blocks. Z indicates the main-line circuit, which includes the electro-magnet K'. X indicates an independent circuit, including a battery, Y'. This circuit may be of any desired length. It is shown as connected with a telephone-receiver, O, sufficiently apart from the magnet K' and the resistance device operated by expansion and contraction of this magnet's core. This apparatus works on the same principle as that described in connection with Figs. 1 and 2. The elongation and contraction of the core of the magnet K' varies the pressure on the carbon blocks and correspondingly varies the current in the independent circuit.

In Fig. 4 is shown a telephone-transmitter, in which several mouth-pieces are arranged in close proximity to each other. These may either be provided with their corresponding electro-magnetic devices for transmitting speech to different points or the local circuits may be united in a single main-line circuit for increasing the volume and distinctness of sound transmitted.

Although it is not new, broadly considered, to combine in telephone apparatus an electro-magnet having a projecting elongating and contracting core and a resistance device operated

by elongation and contraction of said core, I am not aware of any apparatus of this class prior to my invention in which such magnets have been mounted or arranged in frames in 5 which the resistance devices are also arranged, with the cores of the magnets operating upon the resistance devices, as above described and hereinafter claimed.

Having thus described my invention, I 10 claim—

1. The combination, in a telephone apparatus, of the circuit operated by the transmitter and including a battery and the coils of an electro-magnet provided with a projecting elongating and contracting core, the frame in which the magnet is supported, the armature located in said frame at one end of said core, the resistance device located in said frame at the opposite end of the core and directly operated 15 upon by the magnet by elongation of its core, and a second circuit including a battery and the said resistance device, substantially as set forth.

2. The combination of the receiver provided 20 with the diaphragm, the circuit including a battery and an electro-magnet for vibrating the

receiver-diaphragm, and the main line or second circuit including the coils of a supplemental electro-magnet having a projecting core and operating the electro-magnet for vibrating the receiver-diaphragm, and the resistance device against which said core bears, substantially as set forth. 30

3. The combination of the main-line circuit including the electro-magnet with the projecting elongating and contracting core, the rigid frame in which the magnet and its core are mounted and secured at one end, the resistance device at the opposite end of said frame and directly operated upon by the magnet by 35 the elongation of its core, and the independent or local circuit including said resistance device and a battery, and the receiver with which said local circuit is connected, substantially as set forth. 40

In testimony whereof I have hereunto subscribed my name.

PARVIN WRIGHT.
